UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,139,677.

Specification of Letters Patent. Patented May 18, 1915.

Application filed February 13, 1913. Serial No. 748,145.

To all whom it may concern:

Be it known that I, HARRY J. HICK, a citizen of the United States, residing at Alliance, in the county of Alliance and State of Ohio, have invented certain new and useful Improvements in and Relating to Filing Appliances, of which the following is a specification.

This invention relates to a filing appliance adapted to support papers, bills, and the like, in a manner which permits them to be filed, inspected or removed in a rapid and accurate manner.

For the purpose of illustration, I have, in the accompanying drawings, shown and herein described one form of filing appliance embodying my invention.

Figure 1 is a side elevation of a filing appliance embodying my invention, the near side of the casing being broken away to expose the set of holders. Fig. 2 is a fragmentary front view of the appliance, the frontmost holder of which is broken away to expose one of the paper supporting devices on the adjoining holder. Fig. 3 is a fragmentary perspective view of the casing and the guide means for the holders. Fig. 4 is a transverse sectional view of a portion of the casing on the line 4—4 of Figs. 1 and 2. Fig. 5 is a fragmentary view showing the arrangement and details of the connections between the holders.

In the drawings, 1 indicates a casing or housing of any suitable or preferred form of construction adapted to contain a set of holders 2. Preferably the casing comprises a bottom 1^a, a back 1^b, sides 1^c, the lower portions of which may be extended forwardly, a base 1^d and a top or cover 1^e arranged between and supported by the forwardly extended portions of the sides 1^c. The base 1^d may be secured to and supported by the opposite sides 1^c of the casing 1. Below the top 1^e and base 1^d one or more slideable trays may be provided for the purpose of accommodating indexes for the filing sections on the holders 2 and supplies used in connection with the filing system to which the invention is applied. The base 1^d and sides 1^c are relatively wide in order to receive and accommodate additional holders 2

as may be required from time to time to provide for increased filing capacity.

The set of holders 2 comprises a front end holder 2^a, a rear end holder 2^b and intermediate holders 2^c. Each of the intermediate holders 2^c consists of a back 2^d, preferably formed from sheet metal. The holder is provided at its lower end with a hinge bar 2^e, which may be formed by extending the metal of the back 2^d and bending it into a hollow bar.

2^f indicates a plurality of strips secured to the opposite sides or faces of each intermediate holder. These strips are spaced from each other and extend in a longitudinal direction. They serve to space the holders from each other, to strengthen them from edge to edge and to form pockets or sections for the papers to be filed.

2^g indicates the devices for removably supporting the papers, bills, and the like, upon the opposite faces of the intermediate holders. A plurality of paper supporting devices 2^g are provided upon the opposite faces of each intermediate holder in order to provide a large number of filing sections for the papers. Each device is arranged between adjoining strips 2^f and is preferably formed of resilient wire bent to form up and down legs 2^g'. Each leg 2^g' is provided with a coil at its lower end and secured to the adjacent holder in a well known manner.

2^h indicates a plate which connects the legs 2^g' of each device 2^g together. The plate 2^h also serves as a support or back for an index number, abbreviation or eye signal which assists in rapidly filing, inspecting or removing the papers or bills in the operation of the appliance. The front and rear end holders 2^a, 2^b, are constructed similarly to the intermediate holders 2^c, except that the strips 2^f and paper holding devices 2^g are omitted from their opposite outer faces. The holders 2 may be provided at their upper ends with supports 2' for indexes which facilitate the operation of the appliance.

3 indicates suitable connections between the holders 2. The connections 3 serve to pivotally connect the holders together to permit them to swing relatively to each other singly or in groups from a vertical to a hori-

zontal position. As will be readily understood, the connections 3 operate, when one or more of the holders are swung from one position to another, to move those holders which are upright vertically and also to move their lower ends forwardly and rearwardly.

3^a indicates bearing blocks mounted on the base 1^b. The bearing blocks support 10 the pivots for the front end holder 2^a and permit it to swing from one position to another. The bearing blocks 3^a are preferably constructed to permit the disengagement of the pivots for the front end holder therefrom in order that the entire series of 15 holders may be removed from the casing for storage in a safe or vault.

The connections 3 between the holders may be of any preferred form, but the connections 3 between at least two of the holders are of a character which permit the two 20 holders to be separated from each other. The purpose of this construction is to permit the number of holders comprising the 25 set to be increased (see dotted lines in Fig. 1) or decreased at will. In the preferred form of the invention the detachable connections are arranged between the rear end holder 2^b and the adjacent intermediate 30 holder 2^c. When it is desired to increase the number of holders 2, the rear end holder 2^b is detached. The necessary number of 35 new holders 2', shown in dotted lines in Fig. 1, are then secured to the rearmost intermediate holder 2^c, after which the rear end holder 2^b is secured to the rearmost holder 2'. The bearing blocks 3^a are arranged at or near the front edge of the base 1^a in order to provide as much space as possible 40 for the accommodation of such additional holders as may be necessary to care for all the papers or bills to be filed and stored.

4 indicates as an entirety means for supporting and guiding the rear end holder 2^b vertically during the operation of any of the remaining holders comprising the set. I 45 preferably provide two supporting and guiding means 4 arranged at opposite sides of the holders, but as both means are similar in construction it will only be necessary to describe one of them. Of these means 4, 4^a indicates a bar extending in a horizontal direction and arranged between one side of the set of holders 2 and the inner face of the adjacent casing side 1^c. At its front end the bar 4^a is preferably provided with an off-set 4^b, which is secured by a screw or other suitable device 4^c to the side 1^c, the 50 off-set providing for the spacing of the bar away from the face of the side 1^c; and at its rear end the bar 4^a is provided with an ear 4^d which may be secured by a screw or other suitable device 4^d to the back 1^b of the casing, the ear 4^d being preferably se-

cured to the back in a manner which in co-operation with the off-set 4^b, supports the bar 4^a parallel to the side 1^c.

4^e indicates a series of openings formed in the bar 4^a and extending substantially from end to end thereof. Each opening 4^e is adapted to receive and support a supporting member 4^f which projects laterally from the bar 4^a and is arranged to be engaged by the rear end holder 2^b. As shown in the drawings, the supporting member 4^f comprises a stud shaft and has mounted on it a roller 4^g which serves to reduce friction as the rear end moves vertically. The outer end of the shaft 4^f is provided with an annular shoulder which serves to maintain the roller 4^g on the shaft; while its inner end is screw-threaded to take a nut 4^h, which serves to permit removal of the shaft from one opening 4^e when it is desired to insert it in another opening 4^e for purposes of adjustment and coöperation with an increased or decreased number of holders 2.

As will be understood from the drawings, the supporting member 4^f forms a rest or support for the rear-end holder 2^b and permits it to move vertically as any of the holders are operated. The supporting member 4^f is positioned in one of the openings 4^e so that it may coöperate with the bearing blocks 3^a to support the set of holders normally in substantially upright position as shown in full lines in Fig. 1. If additional holders 2' are added to the set of holders, the supporting member 4^f is adjusted along the bar 4^a and is inserted in that one of the openings 4^e which will permit it to coöperate with the bearing blocks 3^a to support the numerically increased set of holders normally in substantially upright position.

The openings 4^e in the bar 4^a are preferably uniformly spaced from each other a distance equal to the thickness of a holder in order that the supporting member 4^f may be adjusted to permit any number of holders to be added to the set.

My construction has the advantage of permitting the filing and storing capacity of the appliance to be increased from time to time without the necessity of purchasing an entirely new filing appliance of a similar or larger size, since one or more holders may be purchased at small cost and added to the set of holders as conditions may require. By the provision of adjustable supporting and guiding means for the rear end holder 2^b, it will be seen that the number of holders 2 may be increased at will without affecting their rapid and accurate operation, appearance, or the distance of the front end holder from the operative. Furthermore, my invention provides for the attainment of these advantages in a simple manner.

To those skilled in the art of making ap-

paratus of the class described, many alterations in construction and widely differing embodiments and applications of my invention will suggest themselves, without departing from the spirit and scope thereof. My disclosures and the description herein are purely illustrative, and are not intended to be in any sense limiting.

What I claim is:

1. In a filing appliance, the combination with a casing having sides, of a set of holders having a support at its front end in the casing, pivotal connections between the holders permitting them to swing relatively to each other, and a normally rigid supporting member projecting laterally from one side of said casing and arranged to be engaged by the rear end holder, the said member being adjustable forward and rearward and coöperating with the front end support to sustain the set of holders normally in upright position and permitting the rear end holder to move vertically with respect to said supporting member as any of the remaining 25 holders are operated.

2. In a filing appliance, the combination of a casing having sides, a set of holders having connections between them permitting the holders to swing relatively to each other, 30 means for supporting the front end holder of the set of holders in the casing, a device for supporting and guiding the rear end holder, and means adjustable forward and rearward for supporting the said device in 35 fixed relation in the casing.

3. In a filing appliance, the combination of a casing having sides, a set of holders having connections between them permitting the holders to swing relatively to each other, 40 means for supporting the front end holder of the set of holders in the casing, and means for guiding and supporting the rear end holder, the said means comprising a horizontal bar arranged between the set of holders and one side of the casing, a supporting 45 member, and means permitting adjustment of said member along said bar.

4. In a filing appliance, the combination of a casing having sides, a set of holders having connections between them permitting the holders to swing relatively to each other, means for supporting the front end holder of the set of holders in the casing, and means for guiding and supporting the rear end holder, the said means comprising a horizontal bar arranged between the set of 50 holders and one side of the casing, and formed with a series of openings, and a supporting member arranged to be removably mounted in any one of said openings, the said openings permitting the said member to be adjusted along the bar.

5. The combination of a casing, a set of 60 holders having connections between them permitting said holders to swing relatively

to each other, the connections between two of said holders being detachable, means for supporting the front end holder of the set of holders in the casing, a normally rigid member for supporting and vertically guiding the rear end holder of the set of holders, and means for adjustably supporting said member, the said adjustable supporting means coöperating with the detachable connections between two of the holders to permit the number of holders in the set to be increased or diminished.

6. In a filing appliance, the combination with a casing having sides, of a set of holders having pivotal connections between them permitting said holders to swing relatively to each other singly or in groups, means for supporting the front end holder of said set of holders in the casing between the sides thereof, of a horizontal bar fixed to each side of said casing and arranged below the upper edges of said holders, and an inwardly extending support removably secured to each of said bars and arranged to be engaged by the rear end holder of said sets of holders, the said support operating as a guide for the rear end holder as any of the remaining holders are operated.

7. In a filing appliance, the combination with a casing having sides, of a set of holders having pivotal connections between them permitting said holders to swing relatively to each other singly or in groups, means for supporting the front end holder of said set of holders in the casing between the sides thereof, of a horizontal bar fixed to each side of said casing and arranged below the upper edges of said holders when in normal position, each of said bars being formed with a series of openings, a shaft removably mounted in one of said openings in each bar, and a roller carried by each shaft and arranged to be engaged by the rear end holder of said set of holders, the said openings permitting adjustment of the shafts longitudinally of the bars and the rollers operating as guides for the rear end holder as it moves vertically.

8. In a credit register, in combination with a cabinet and a bank of leaves pivotally mounted in said cabinet, an adjustable back leaf support adapted to be fixedly connected to said cabinet in various positions, front-to-rear, and adapted to engage the rear leaf of said bank, to maintain the same in vertical position.

9. In a credit register, in combination with a cabinet and a bank of leaves such as described, spaced supporting pins adjustably connected to the two sides of said cabinet and adapted to receive and support the rearmost leaf of said bank.

10. In a credit register, in combination with a cabinet and a bank of leaves pivotally mounted therein, as described, spaced,

horizontally disposed, front-to-rear-extending bars each provided with a front-to-rear series of apertures and rear leaf supporting means including a pin adapted to be arranged in any one of said apertures and to receive and support the rear leaf of said bank.

In testimony whereof I affix my signature, in the presence of two witnesses.

HARRY J. HICK.
